Term of patent 14 years

(Cl. D54—1)

FIG. 1.

FIG. 2.

FIG. 3.

FIG. 4.

FIG. 5.

FIG. 6.

FIG. 7.

FIG. 8.

FIG. 1 is a perspective view of a coat hook showing my new design;

FIG. 2 is an elevational view taken from one side thereof and shows the coat hook in a position of non-use;

FIG. 3 is a front elevational view thereof;

FIG. 4 is a rear elevational view thereof;

FIG. 5 is a top view of the same;

FIG. 6 is a bottom view of the same;

FIG. 7 is a sectional view thereof taken substantially on line 7-7 of FIG. 4; and

FIG. 8 is an elevational view thereof similar to FIG. 2, but showing the coat hook in a position of use.

The fragmentary broken line representation of a coat hook assembly in the several figures is for purposes of illustration only.

I claim:

The ornamental design for a coat hook, substantially as shown and described.
